UNITED STATES PATENT OFFICE.

REDMOND A. MACCARTHY, OF CHICAGO, ILLINOIS, ASSIGNOR TO LOUISE B. WELLS AND DOROTHY P. SMITH, BOTH OF CHICAGO, ILLINOIS, AS TRUSTEES FOR THE SOLE USE AND BENEFIT OF A VOLUNTARY ORGANIZATION KNOWN AS "WOMEN'S OVERSEAS SERVICE LEAGUE."

DESIGN FOR A BADGE FOR PERSONAL WEAR.

Application filed May 24, 1924. Serial No. 9,699. Term of patent 14 years.

To all whom it may concern:

Be it known that I, REDMOND A. MACCARTHY, a citizen of the United States, residing at Chicago, in the county of Cook and State of Illinois, have invented a new and original ornamental Design for Badge for Personal Wear, for the organization known as "Women's Overseas Service League," of which the following is a specification, reference being had to the accompanying drawing, forming a part hereof.

I claim:

The ornamental design for a badge for personal wear as shown.

In witness whereof I have hereunto set my hand at Chicago, Illinois, this 19th day of May 1924.

REDMOND A. MACCARTHY.
